ELECTRIC SCISSORS

Henry Leong and Paul A. Witte, Kendall Park, N.J., assignors to Scovill Manufacturing Company, Waterbury, Conn., a corporation of Connecticut

Filed Dec. 11, 1967, Ser. No. 9,740

Term of patent 14 years

(Cl. D95—5)

Fig. 1

Fig. 2

Fig. 3

Fig. 4Fig. 5Fig. 6

FIG. 1 is a top perspective view of an electric scissors showing our new design, the blades having been omitted for convenience of illustration;

FIG. 2 is a front view;

FIG. 3 is a rear view;

FIG. 4 is a top view;

FIG. 5 is a side view; and

FIG. 6 is a bottom view.

The dominant features of the new design are shown in full lines.

We claim:

The ornamental design for an electric scissors, as shown and described.
